UNITED STATES PATENT OFFICE.

ANDREW E. MACCOUN AND MICHAEL KILLEEN, OF BRADDOCK, PENNSYLVANIA.

LADLE FOR MOLTEN METAL.

No. 914,738.

Specification of Letters Patent.

Patented March 9, 1909.

Application filed January 31, 1908. Serial No. 413,539.

To all whom it may concern:

Be it known that we, ANDREW E. MACCOUN and MICHAEL KILLEEN, both of Brad-
dock, Allegheny county, Pennsylvania, have
5 invented a new and useful Improvement in
Ladles for Molten Metal, of which the fol-
lowing is a full, clear, and exact description,
reference being had to the accompanying
drawings, forming part of this specification,
10 in which—

Figure 1 is a side elevation of our improved
ladle; Fig. 2 is a sectional side elevation on
the line II—II of Fig. 1, the left hand side of
each of these views showing the outline of the
15 skull as it forms in the ladle, the right hand
side showing a newly lined ladle.

Our invention relates to the ladles which
are used in conveying molten metal and it
20 more particularly relates to ladles which are
placed upon ladle cars and are used in trans-
porting molten metal from one place to
another.

Heretofore in such ladles the metallic shell
25 has been provided with a lining composed of
brick or other refractory material. After
these ladles have been used for a short time,
a skull forms in such ladles which very ma-
terially reduces their capacity. The skull
30 forms quicker on the top of the ladles at
about the level of the metal when the ladle is
full. This causes the skull on the top of the
ladle to be thicker than that formed upon the
bottom and sides of the ladle. Usually the
35 skull forms on the top portion of the ladle to
such an extent that it is impossible to entirely
drain the molten metal from the ladles, the
hump or projection formed by the skull on
the top portion of the interior of the ladle
40 forming a stop or dam which retains a quan-
tity of the molten metal in the ladle, which if
not removed will solidify in the ladle.

Our invention is designed to provide a
ladle in which these difficulties are overcome
and by which the time required in relining
the ladles is greatly reduced and the life of
such linings is largely increased.

The invention is further designed to pro-
vide improved means for removing the large
skull which forms in the top of the ladle at
the level of the metal when the ladle is full
without removing the entire lining from the
ladle.

The invention consists in constructing a
sectional ladle in which the top metallic shell
portion is removably secured to the lower
metallic shell of the ladle.

It also consists in constructing the ladle so
as to bring the joint between the sections at
such point as will permit the large upper por-
tion of the skull to be removed with the re- 60
movable top section of the ladle.

In the drawings, 2 represents the lower me-
tallic shell of the ladle which is provided with
a refractory lining 3. 4 is the metallic shell
of the upper removable top portion or sec- 65
tion of the ladle which also is provided with a
refractory lining 5. The top section of the
ladle is provided with the usual pouring
spouts 6. The ladle is placed in the trunnion
ring 7 having the trunnions 8 by which the 70
ladle is mounted upon the ladle car and the
ladle is also provided with straps 9 having
holes 10 through which may be inserted chain
hooks or other devices by which the ladle is
handled in removing it from and replacing it 75
in the trunnion ring 7. The top section 4 of
the metallic shell is secured to the lower sec-
tion 2 by means of bolts 11 and keys 12 which
secure together the horizontal legs of the
lugs 13 and 14. Suitable angle plates 15 are 80
provided on the top rim of the lower ladle
section 2 and on the top and bottom rim of
the upper section 4 to retain the bricks or
other refractory lining in place and prevent
the lining from becoming dislodged. 85

When the ladle has become skulled after
being used for some time and it is desirable
to remove the skull which forms in the top
portion of the ladle in order that the molten
iron may be entirely drained from the ladle 90
or to again bring the ladle to somewhere
near its normal capacity, the bolts 11 are
removed from the lugs 13 and 14 and the top
section 4 of the ladle is lifted from the bot-
tom section 2. The skull formed in the 95
bottom portion of the ladle will frequently
be removed from the bottom portion of the
ladle in removing the top portion of this
ladle or the skull will be broken around the
line of the meeting edges or joint of the 100
ladle sections. A newly lined top section of
the ladle is then easily and quickly placed in
position on the bottom section 2 and is
secured to this section by means of the bolts
11 as before. The ladle is then in readiness to 105
be again used in transporting molten metal.
The skull can then be removed from the top
section 4 of the ladle which has been taken
from its place on the bottom section 2.
Usually this operation causes the lining of 110
the top section of the ladle to be broken or
become loosened to such an extent that it is

22
necessary to reline this top section of the ladle.

The advantages of our invention arise from the increased life of the lining in the lower portion of the ladle, as a number of the top sections can be used without the necessity of relining the bottom section. The expense of keeping the ladles in condition to carry a maximum amount of molten material and 10 in keeping them in condition to be entirely drained after each filling operation is very largely reduced as by removing the top section and replacing it with a fresh top section the pool of metal which is generally 15 impossible to remove from the top of the ladle after it has been used for some time is then easily drawn from the ladle and the capacity of the ladle is larger.

The apparatus is simple and is easily kept 20 in repair. By keeping a number of extra top sections the equipment necessary to handle a large amount of molten metal is less than when the ladles are made in the usual manner.

25 We claim:—

1. A sectional open top ladle for molten metal having a metallic shell, a separable refractory lining for each section of the shell, means to retain the refractory lining in each 30 section and detachable means for securing the shell sections together; substantially as described.

2. An open top ladle for molten metal having a lower metallic shell portion, a refractory lining in said shell portion, an 35 upper metallic shell portion removably secured to said lower portion, the inner face of the metallic shells being in alinement with each other, a separable refractory lining 40 for the upper shell portion, and means for securing the upper to the lower shell portion; substantially as described.

3. An open top ladle for molten metal having a metallic shell and a refractory 45 lining within said shell, said ladle having a

separable upper shell portion and its lining, detachably secured to a lower shell portion, and means to retain the refractory lining in each section; substantially as described.

4. An open top ladle for molten metal 50 having a sectional separable metallic shell, an independent refractory lining in each section of the shell means to retain the refractory lining in each section, and means for separably securing together the lined 55 sections of the shell; substantially as described.

5. A ladle for molten metal having a removable open top section and means for securing the removable section to the body 60 portion of the ladle, the top section and body portion having separable refractory linings whose inner surfaces are alined to form a continuous lining of gradually increasing 65 diameter toward the top; substantially as described.

6. A ladle for molten metal, consisting of a body portion having a trunnion ring surrounding its upper edge portion, a shallow 70 removable interchangeable top section carrying the pouring lips, said portion and section being detachably connected and having separate refractory linings, and means to retain the lining in the top section and body portion; substantially as described.

7. An open top ladle section for molten metal having a metallic shell and a refractory lining within said shell, said ladle having a separable upper shell portion and lining 75 removably secured to the lower shell portion, and angle bars secured to the inner walls of each shell for retaining the refractory lining, substantially as described.

In testimony whereof, we have hereunto set our hands.

ANDREW E. MACCOUN.
MICHAEL KILLEEN.
